CATENULIN AND ITS PRODUCTION

Jacob W. Davisson, Floral Park, and Alexander C. Finlay, Flushing, N.Y., assignors to Chas. Pfizer & Co., Inc., Brooklyn, N.Y., a corporation of Delaware

No Drawing. Application March 11, 1954
Serial No. 415,688

9 Claims. (Cl. 167—65)

This invention relates to a new biologically active substance designated as P.A. 88 or catenulin. More particularly it concerns processes for production and recovery thereof from cultures of a hitherto unknown microorganism which has been designated *Streptomyces catenulae* and which will be more fully described hereafter. 15 This application is a continuation-in-part of our copending application Serial No. 190,436, filed October 16, 1950, and now abandoned.

The new microorganism, *Streptomyces catenulae*, has been isolated from a sample of soil and found to differ from the known species of Streptomyces listed in the accepted classification of Bergey's "Manual of Determinative Bacteriology" (6th edition), pages 928—980. The cultural characteristics of this species, based on isolate No. 5541-6A of Chas. Pfizer & Co., Inc., are given below 25 in tabular form. (The colors, where R is written, are those of Ridgway, Color Standards and Nomenclature.) Readings were determined on six tubes or plates. The specific name chosen for this newly isolated microorganism indicates the short chains of spores which it produces, one of its distinctive characteristics. A living culture of the organism has been deposited with the American Type Culture Collection at Washington, D.C., and has been added to its permanent collection of micro- 30 organisms as ATCC 12,476.

2

It is to be understood that the production of catenulin is not limited to this particular organism or to organisms fully answering the above description, which is given merely for illustrative purposes. Those organisms are especially contemplated which are mutants produced from the described bacterium by mutating agents such as X-radiation, ultraviolet radiation, nitrogen mustards and so forth.

In order to measure the potency of various solutions or solid preparations of catenulin, an essay procedure is used in which is determined the turbidity of standard cultures of a *Staphylococcus aureus* strain grown in a standard test medium in the presence of varying amounts of the given sample of catenulin. An arbitrary standard has been chosen, based on a sample of catenulin which assayed 3200 CDU/mg. in the *E. coli* dilution test described below. A value of 1000 catenulin units per milligram has been assigned to this preparation. The test medium is the Baltimore Biological Laboratory assay broth, prepared according to the Food and Drug Administration formula for streptomycin assay broth, and the method used is that of J. R. McMahan (J. Biol. Chem., vol. 153, pages 249—258, April 1944).

Catenulin possesses activity against a wide variety of organisms. However, its activity against the usual gram positive and gram negative microorganisms is somewhat limited as compared to its activity against the mycobacteria. The following table shows the spectrum of catenulin against a group of gram positive and gram negative bacteria, as well as certain molds. These tests were conducted by streaking standard cultures of the microorganisms on agar plates containing varying known concentrations of a preparation of catenulin. The levels tested were 100, 50, 25, 10, 5 and 1 micrograms of catenulin per milliliter of agar medium. In the table below is given the minimum concentration within these ranges which completely inhibited the growth of the streaked microorganism culture during 24 hours' incubation at 37° C. The preparation of catenulin used in 40 this series of tests had an activity of 6400 *E. coli* dilu-

Streptomyces catenulae (ATCC 12,476)

Medium	Amount of Growth	Color		Remarks
		Aerial Mycelium and Spores	Soluble Pigment	
Glucose-asparagine agar	Moderate to good	Moderate sporulation near Mouse Gray (R); white aerial mycelium at edge.	Faint yellowish	Colony slightly elevated in center; surface concentrically and radiately wrinkled; sporulated surface rough and granular; smooth edge; reverse dark brown or dark greenish brown; spores in very short clustered chains; clusters very dense; a few fairly tight spirals; spores oval to short cylindrical, 1.0 x 1.32. Color of sporulated colonies on dilution plates between Dark Olive Gray (R) and Hair Brown (R); colonies alike. Poor liquefaction.
Gelatin plates, 21° C	Moderate spreading	Waxy, near Cartridge Buff (R); some white aerial mycelium.	None	
Glucose agar	Good	Good sporulation, near Pale Drab-Gray (R); waxy edge Olive-Buff (R); some white aerial mycelium.	Yellow	Reverse yellowish brown.
Nutrient agar	Moderate	Abundant white aerial mycelium; slight sporulation, a very pale gray.	Pale Yellow	Reverse pale yellow.
Potato Plugs	Good	Good sporulation from Pale Olive (R), Smoke Gray (R), and Hair Brown (R).	Dark greenish, occasionally no soluble pigment.	Greenish vegetative mycelium.
Calcium malate agar	Poor	Good sporulation, near Pallid Mouse Gray (R); some white aerial mycelium.	None	Reverse not visible; calcium malate digested.
Starch plates	do	Waxy, light brownish orange; poor sporulation near Deep Mouse Gray (R).	do	Reverse light brownish orange; good hydrolysis of starch.
Synthetic agar	Very poor spreading	Sporulation light gray	do	Transparent, deep white subsurface growth; reverse transparent, white.
Cellulose strips	Very poor growth			
Emerson's agar	Moderate	Good sporulation, near Olive-Gray (R); white aerial mycelium.	Medium brown	Reverse very dark brown.
Dextrose nitrate broth				Nitrate not reduced.

tion units per milligram of dry solid, i.e. one milligram of the preparation diluted to 6400 milliliters just inhibited a standard culture of *Escherichia coli* grown in a suitable nutrient medium for 18 hours at 37° C.

TABLE I

Microorganism:	Concentration of catenulin preparation, mcg./ml.
<i>A. aerogenes</i> ¹	25
<i>A. aerogenes</i>	50
<i>E. coli</i>	25
<i>Proteus</i> sp.	50
<i>B. subtilis</i>	10
<i>Micrococcus pyogenes</i> var. <i>aureus</i>	10
<i>Str. faecalis</i>	25
<i>Brucella bronchiseptica</i>	(2)
<i>Sal. paratyphi</i> B	50
<i>Candida albicans</i>	(2)
<i>Sal. typhosa</i>	25
<i>K. pneumoniae</i>	25
<i>Sal. paratyphi</i> A	50
<i>Ps. aeruginosa</i>	(2)
<i>Trichophyton mentagrophytes</i>	(2)

¹ Resistant to chlortetracycline ("Aureomycin") and chloramphenicol ("Chloromycetin").

² Growth at 100 mcg./ml.

The activity of catenulin has also been measured against a group of mycobacteria in the same manner as de-

4 protein supplement (A.P.S.) to provide a positive control, i.e. a nutritionally balanced feedstuff supplying all of the normal requirements of the chicks. The basal ration so employed had the following composition:

5	Yellow corn meal	percent	52.2
	Soybean oil meal	do	22
	Middlings	do	10
	Alfalfa leaf meal	do	3
10	Fish meal	do	4
	Meat scraps	do	4
	CaCO ₃	do	1.8
	Dicalcium phosphate	do	1
	Salt	do	0.5
	Viadex	do	0.13
15	MnSO ₄	gm./100 lb	10
	Choline chloride 25%	do	312
	Thiamin	do	90
	Riboflavin	do	160
	Calcium pantothenate	do	545
20	Niacin	do	800
	Pyridoxine	do	160

The results of these tests are summarized in the following table. For the purposes of comparison, some of 25 the groups were fed rations supplemented with oxytetracycline hydrochloride, a highly effective growth promoting antibiotic sold under the registered trademark "Terramycin."

TABLE III

Group	Supplement to Diet	Supple- men- ta- tion, mg./kg.	Average Body Weight—weeks					Net Gain	Growth Index	Feed Effi- ciency
			0	1	2	3	4			
1	Positive Control (P)		45	87	154	259	339	294	100	2.15
2	P+catenulin	2	42	88	164	273	368	326	108	2.09
3	do	5	45	92	174	282	391	346	115	2.02
4	do	10	45	92	164	268	388	343	114	2.08
5	P+oxytetracycline HCl	2	42	93	171	281	388	346	114	1.91
6	do	5	42	93	168	276	380	338	112	2.02
7	do	10	42	84	158	260	364	322	107	2.12

scribed above and using the same preparation. The compound shows an unexpectedly high order of activity against this group of microorganisms (Table II). The preparation here used was prepared in accordance with Example I below.

TABLE II

Mycobacterium:	Concentration of catenulin, mcg./ml.
<i>Mycobacterium ranae</i>	5
<i>Mycobacterium phlei</i>	3
<i>Mycobacterium smegmatis</i>	5
<i>Mycobacterium</i> species No. 607	5
Comparable activity is demonstrated against human strains of <i>Mycobacterium tuberculosis</i> .	

The marked specificity of catenulin against mycobacteria, as compared to its activity against other types of microorganisms, is a rather unique property of the substance and further illustrates its marked difference from most known antibiotics, such as penicillin, streptomycin, oxytetracycline ("Terramycin"), chlortetracycline ("Aureomycin"), chloramphenicol ("Chloromycetin"), streptomycin, etc. While utility of the antibiotic in human therapy has not as yet been demonstrated, it is particularly useful in promoting the growth of animals.

A series of tests were conducted with catenulin to determine its effects on the growth of chicks. In these tests the chicks were divided into groups and fed a basal ration supplemented with various proportions of catenulin, in the form of the sulfate, over a period of four weeks, during which the average weight, growth response and feed efficiency were recorded for each group.

The basal ration was supplemented with 8% animal

45 In the above table growth index is a measure of growth response (in terms of weight) to the antibiotic supplementation in relation to the basal ration or positive control without such supplementation, the higher the index the greater the response. The positive control is arbitrarily assigned a value of 100 to provide a basis for comparison. Feed efficiency is the ratio of the weight of feed required per unit weight of growth increase, the lower the ratio the higher the efficiency of the particular feed.

50 From the above tests it is apparent that catenulin supported increases in the growth of chicks ranging upward to 15% over the controls at the levels of catenulin supplementation employed. It is further apparent that catenulin supports growth increases in chicks comparable to the increases obtainable with oxytetracycline. Additional tests with catenulin have confirmed these results.

55 Catenulin has been distinguished from known antibiotics by its antimicrobial spectrum and by a number of other properties. For instance, its behavior when chromatographed on paper, using various solvent systems, is distinct from the various compounds heretofore mentioned. Further, it is not appreciably extracted or flushed from its dilute aqueous broth solutions into the usual solvents at acid, neutral, or basic pH's, as are penicillin and the like materials. It also possesses a quite high degree of stability. It can be maintained at a lowered 60 or raised pH for appreciable time without undue loss, although heating for extended periods in an acid medium tends to decrease its activity. Our new biologically active substance contains the elements carbon, hydrogen, oxygen and nitrogen, but no sulfur, phosphorus, or halo-

75 gen.

Catenulin has a low order of toxicity. Thus, a sample of the material having a potency of 6400 *E. coli* dilution units per milligram (CDU/mg.) was found, on intravenous injection into mice, to have an LD₅₀ of 4.5 milligrams per mouse. The LD₅₀ for the same animal, also using intravenous administration, was 6.0 milligrams.

This invention also embraces processes for growing the hitherto unknown species of microorganism, *Streptomyces catenulæ*. Such processes involve cultivating the bacterium in a suitable nutritive medium, preferably at about 22° to 32° C. under aerobic conditions and with agitation. The standard culture media contain a source of carbohydrate, such as sugars, starch and glycerol; a source of organic nitrogen, such as bean meals and particularly soybean meal, wheat gluten, cotton seed meal, lactalbumin, and enzymatic digests of proteins; and a growth-promoting substance, such as distillers solubles and yeast extracts. Mineral salts like sodium chloride, sodium nitrate, and potassium phosphate, a buffering agent like calcium carbonate and a vegetable or mineral oil are usually also incorporated therein. After growth for a suitable time until an appreciable antibiotic potency has been imparted to the medium, generally a period of about one to five days, the mycelium which is formed is usually separated from the broth containing the elaborated catenulin, and the latter is then recovered by various procedures.

It is anticipated that there will be certain moieties within the catenulin chemical structure, which will be useful as precursors for the preparation of the substance by fermentation.

Inoculum for the commercial preparation of catenulin may be obtained from growth in slants or Roux bottles inoculated with a strain of *Streptomyces catenulæ*. Solid media suitable for this initial growth of the microorganism are e.g., beef lactose or Emerson's agar. Such growth may then be used to inoculate either shaken flasks or inoculum tanks for submerged aerobic cultivation. Alternatively, inoculum tanks may be later inoculated from shaken flasks after the latter have been cultivated for a suitable period. The growth in shaken flasks generally reaches its maximum in two to four days. After a suitable period of incubation, the contents of the inoculum tanks may be added to larger fermenters under aseptic conditions and cultivation in the new medium continued for one to five days. In the inoculum tanks and in the large scale fermenters, agitation is preferably continued throughout the fermentation by blowing in sterile air through spargers at the rate of about 1/2 to 2 volumes of free air per volume of broth per minute and by stirring at speeds of 100 to 2000 r.p.m. If foaming is encountered during the growth, it may be controlled by the addition of suitable foam-controller such as vegetable oil, mineral oil, a silicone, octanol or the like. When grown in this manner, *Streptomyces catenulæ* furnishes broths containing from about 200 to about 5000 CDU/ml. of the catenulin.

The catenulin may be recovered by a variety of methods from fermentation broths produced by the methods described above. The solid mycelial growth should first be removed from the broth by filtration. It is preferable to acidify the mixture before this clarification, in order to achieve maximum separation of the catenulin from the mycelia, and a filteraid may also be employed to assure a broth of high clarity. The biologically active substance may then be removed from the filtrate by adsorption at about a neutral pH on solid adsorbents like carbon or cation-exchange resins (e.g. of the carboxylic or sulfonic acid types). Various organic solvents such as methanol, ethanol or acetone, either dry or containing water, and preferably containing some acid, are utilized to elute the substance from carbon, while dilute acids like hydrochloric, sulfuric or acetic serve in the elution of resinous adsorbates. The eluates are finally neutralized and dried to recover products of elevated catenulin activ-

ity. Such products may be used directly in therapy or purified still further by conventional means.

Another very useful method of isolating and recovering catenulin from its fermentation broths is by precipitation with various arylazosulfonic acid dyes. These materials readily form salts with the substance which have a low degree of solubility. The precipitates are generally prepared with the broth at a pH of about 5 to 8, and the salt products may be filtered from the exhausted broth. If difficulty is encountered with the filtration, a suitable filteraid may be utilized. The solid dye salts of catenulin may be used as such or further treated to regenerate a purified form of the substance. Among the particularly useful dyes are Eriochrome Violet, Orange II, Helianthine, Naphthol Blue-Black, Polar Yellow, Fast Red. These have respectively the Color Index numbers 169, 151, 150, 246, 642 and 176. Of these the first is especially satisfactory in commercial operations. Recovery of the catenulin from such dye salts is accomplished in various ways. One preferred method is to treat a solvent solution thereof with an amine salt of an acid, which salt is soluble in the chosen solvent but in turn forms a solvent-insoluble salt with the catenulin. Triethylamine sulfate in methanol is a most suitable combination. A metallic salt may be used instead of an amine salt. Thus, if an arylazosulfonic acid salt of catenulin is treated in a solvent with barium chloride, the barium salt of the dye will separate and a solution of the catenulin hydrochloride is obtained. It is obvious that metallic salts other than barium chloride may be used, the only limitations being that the dye salt of the metal used be insoluble in the chosen solvent and the acid salt of the catenulin formed during the metathetical reaction be soluble in that solvent. By removal of the solvent from the filtered solution, a dry biologically active product is finally obtained. A further method for converting arylazosulfonic acid salts of catenulin is by treatment with a suitable dilute solution of a strong acid, such as sulfuric acid or hydrochloric acid. This results in the formation of the free arylazosulfonic acid, which has a limited solubility in water and lower alcohols. The dye may then be removed by filtration and any traces thereof remaining in the solution adsorbed therefrom by activated carbon or the like. The resulting filtrate containing an acid salt of catenulin in solution may be evaporated to yield a dry preparation of the substance. Rather than filtering the arylazosulfonic acid, it may be extracted with a solvent such as butyl alcohol or amyl alcohol.

These various purification methods may be repeated or may be used in combination with one another to obtain products of increased purity. In addition, the antibiotic may be separated from various inorganic salt impurities by selective extraction of a dry sample with a suitable solvent. Materials prepared by the above procedures have been shown by paper chromatography, using various solvent systems, to contain only the one compound, catenulin.

A particularly useful procedure whereby catenulin may be highly purified involves the formation of the helianthate of this compound which salt has been obtained in crystalline form. Thus, if a sample of a simple catenulin salt, such as the sulfate or hydrochloride, assaying about 1500 catenulin units per mg. or higher, is treated in aqueous solution with a soluble helianthate such as an amine salt of helianthic acid (pyridine helianthate, triethylamine helianthate, and so forth), there is obtained the crystalline helianthate. This compound may be recrystallized from a solvent such as methanol containing a major proportion of water. Other lower alcohols or ketones may also be used. Crystalline catenulin helianthate does not melt below 300° C., but it does darken slightly at temperatures above 240° C. It consists of fine red-brown needles when prepared as described above. This crystalline salt has an assay of about 1200 catenulin units per mg. In addition to the helianthate a crystalline

reineckate has been obtained by treating the catenulin in water with ammonium reineckate.

From the helianthate it is possible to regenerate highly purified preparations of simple salts of catenulin such as the hydrochloride or sulfate. One method of doing this is to dissolve the crystalline salt in methanol and then treat the solution with concentrated hydrochloric acid. Crystalline helianthic acid separates and may be removed by filtration. Small amounts of dye left in the solution may be removed by a decolorizing agent and catenulin hydrochloride may then be recovered by a method such as precipitation from a solvent in which it has low solubility, e.g. acetone.

The p(p'-hydroxyphenylazo)-benzene sulfonic acid salt of catenulin has also been crystallized, and the simple sulfate salt regenerated therefrom by treatment in methanol with triethylamine sulfate and drying (e.g. in vacuum at 100° C.). The sulfonic acid compound analyzes about 50.24% by weight of carbon, 5.29% hydrogen, 10.01% nitrogen and 8.00% sulfate. It has an optical rotation of $[\alpha]_D^{25} = +33^\circ$ (1% in methanol). The sulfate analyzes about 31.53% by weight carbon, 6.0% hydrogen, 7.92% nitrogen and 28.11% sulfate; its optical rotation is

$$[\alpha]_D^{25} = +51.9^\circ \text{ (1% in water)}$$

The ultraviolet spectrum shows only end absorption and the infrared absorption is typical of a polypeptide, i.e. there are no characteristic sharp bands as in simpler organic molecules.

The following examples are given to illustrate the manner in which catenulin may be prepared, recovered, concentrated, and converted to purified, solid form. Various other alternative procedures will be apparent to those skilled in this art.

Example I

A medium containing water and the following proportion of ingredients by weight was prepared:

	Percent
Cerelose	1.0
Sodium chloride	0.5
Distillers' solubles	0.5
Enzymatic hydrolysate of casein	0.5

After this solution had been prepared it was adjusted to pH 7 with potassium hydroxide and 0.1% of calcium carbonate was added. A small amount of a vegetable oil as an anti-foaming agent was added. The liquid was dispensed to Fernbach flasks, 500 milliliters in each. The flasks were plugged with cotton and were sterilized at 25 pounds of steam pressure for 45 minutes. The pH of the mixture had decreased to 6.5. This nutrient medium was inoculated from a slant of *Streptomyces catenulæ* ATCC 12,476 which had been grown on beef lactose agar. The flasks were shaken for two days at 28° C. on a rotary shaker. One liter of this inoculum was then added under sterile conditions to 20 gallons of the same type of nutrient medium, which had previously been sterilized and cooled in an inoculum tank equipped for submerged fermentation. This inoculated mixture was stirred and aerated at the rate of about one volume of air per volume of medium per minute for one day, while the temperature was maintained at 27° C.

The contents of the inoculum tank were forced under aseptic conditions into 150 gallons of the same type medium, which had been sterilized and cooled. This mixture was subjected to aeration and rapid stirring for a period of 43 hours at a temperature of about 27° to 28° C. After 41 hours of growth the mixture had a catenulin potency of 320 CDU/ml. The broth was adjusted to pH 5.6 with dilute sulfuric acid, 10 pounds of a diatomaceous earth filteraid were added, and the material was thoroughly stirred and filtered. To the clear filtrate were added 900 grams of Eriochrome Violet. The mixture was stirred for half-an hour and filtered

with a filteraid. The filtercake was washed several times with water, to remove adhering exhausted broth, and then dried.

One-half of this filtercake was added to 12 liters of 5 90% methanol. A solution of 2500 milliliters of 50% triethylamine sulfate in methanol was slowly added to the mixture. After stirring for one hour, the catenulin sulfate salt, mixed with filteraid, was removed by filtration and washed by slurring three times with six liters of 10 methanol and one time with six liters of acetone. Practically all of the dye was removed by this treatment. The filtercake obtained after the last wash was sucked free of solvent and then suspended in 2500 milliliters of 15 water. It was filtered to remove filteraid and washed with a small volume of water. The resulting clear, aqueous solution was dried under vacuum from the frozen state. The product so obtained was dissolved in a small volume of water (600 ml.). A small amount of insoluble material, apparently inorganic salts, was removed 20 by filtration and the filtrate was again dried from the frozen state. The product weighed 6.0 grams and assayed 6400 CDU/mg. This product was particularly active against mycobacteria and in promoting the growth of chicks; it possessed a relatively low degree of toxicity.

Example II

A sample of 5.0 grams of catenulin sulfate obtained as in the example above and assaying 1675 catenulin units per mg. was dissolved in 10 ml. of water. Five 30 ml. of a saturated aqueous ammonium oxalate solution was added to remove calcium. The precipitate was centrifuged and the supernatant liquid was removed. This solution was treated with 100 ml. of an aqueous solution containing 10 grams of helianthic acid as its pyridine salt. 35 The slow addition of this reagent caused the formation of crystalline catenulin helianthate in the form of fine red-brown needles. These were separated by centrifugation and were washed by suspension in hot water. After the suspension had been filtered the product was dried. 40 It weighed 14 grams and assayed 1200 catenulin units per mg. A sample recrystallized twice from 33% methanol did not melt up to a temperature of 300° C., but slight darkening of the sample occurred at 240° C.

Example III

Five grams of crystalline catenulin helianthate prepared as in the example above was dissolved in 50 ml. of methanol. To the solution was slowly added 2 ml. of concentrated hydrochloric acid. The solution was stirred 50 during the addition of the addition of the acid. The crystalline helianthic acid that separated was filtered and the purple solution was passed through a bed of a decolorizing carbon (Darco G60). The clear, practically colorless solution was then added slowly to 5 volumes 55 of acetone with stirring. The precipitated catenulin hydrochloride was filtered and dried. It weighed 1.25 grams and assayed 3740 catenulin units per mg.

As many apparently widely different embodiments of this invention may be made without departing from the 60 spirit and scope hereof, it is to be understood that the above invention is not limited except as defined in the appended claims.

What is claimed is:

1. A process for producing catenulin, which comprises cultivating *Streptomyces catenulæ* under submerged aerobic conditions in an aqueous nutritive medium containing a growth-promoting substance, carbohydrate and organic nitrogen, until substantial antibacterial activity is imparted to said medium.
2. A process for producing catenulin, which comprises growing *Streptomyces catenulæ* for between about one and five days under submerged aerobic conditions with agitation in an aqueous solution maintained at a temperature of substantially from 22° to 32° C. and containing 75 a growth-promoting substance, carbohydrate and organic

nitrogen, and then recovering from the broth the catenulin thus elaborated.

3. The process of claim 2 wherein the recovery of the catenulin includes the operations of clarifying the broth, adsorbing the catenulin from the clarified broth with a solid absorbent, and eluting the absorbate. 5

4. The process of claim 2 wherein the catenulin is recovered as a salt by precipitation from the broth with an arylazosulfonic acid dye selected from the class consisting of Eriochrome Violet, Orange II, helianthine, naphthol blue-black, Polar Yellow and Fast Red. 10

5. A new biologically active substance identified as catenulin, which is prepared by the process of claim 1, and the acid salts of said substance.

6. A new biologically active substance identified as catenulin, which is prepared by the process of claim 1. 15

7. A hydrochloride of the substance claimed in claim 6.

8. A sulfate of the substance claimed in claim 6.

9. A helianthate of the substance claimed in claim 6. 20
